UNITED STATES PATENT OFFICE.

RENÉ E. DUPLESSIS, OF BEVERLY, MASSACHUSETTS, ASSIGNOR TO UNITED SHOE MACHINERY CORPORATION, OF PATERSON, NEW JERSEY, A CORPORATION OF NEW JERSEY.

SHOE-PRESSING MACHINE.

Application filed April 30, 1927. Serial No. 187,858.

This invention relates to machines for applying pressure to the bottoms of boots and shoes, and is illustrated herein as embodied in a heel-seat forming machine arranged to 5 apply molding pressure to the heel-seat portions of shoes to prepare the shoes for the reception of wood heels, the machine being of the general type disclosed in my prior application Serial No. 36,922, filed June 13, 1925.

10 In the manufacture of shoes to which wood heels are to be applied, it is usual to trim the surplus stock from the heel-seat portions of the soles of the shoes by beveling the edges of the heel-seat portions of the soles to bring 15 them to a shape approximately complementary to that of the attaching surfaces of the wood heels which are to be attached. In order to provide a solid heel-seat and to cause the heel-seat portion of the sole of the shoe to contact 20 over the greater portion of its area with the attaching surface of the wood heel that is to be attached, heel-seat forming or molding machines have come into use. A heel-seat forming machine is commonly provided with 25 a mold or a pair of molds or dies readily changeable in accordance with the size and shape of the shoe to be operated upon, a work support or a pair of work supports, and means for causing relative movement of each 30 mold or die and the corresponding work support so as to apply a heavy molding pressure to the heel-seat portion of a shoe mounted upon a last carried by the work support.

An object of this invention is to provide, 35 in connection with mechanism for applying the heavy molding pressure, improved measuring means by virtue of which the pressure-applying movements of the pressure-applying means will be uniformly effective irrespective of variations in the heights or thicknesses of different work pieces operated upon. With this object in view the illustrated machine comprises a movable support for a shoe on a last, a heel-seat forming mold or die 40 mounted upon a carrier which is movable toward the shoe into preliminary engagement with the shoe, means for preventing reverse movement or regression of the die carrier after the die has been brought into contact 45 with the heel-seat and the shoe properly located relatively thereto, and power mechanism by which the work support may be operated to force the shoe against the die with 50 heel-seat forming pressure. In the illustrated machine, the mold or die and its carrier are movable toward the shoe manually, 55 for example by means of a treadle, and the carrier is held against regressive movement by means of a one-way clutch such as a roller clutch which acts automatically to hold the die in the position to which it is depressed. The illustrated shoe support is arranged to swing into and out of position under the die so that a shoe placed on the support may be 60 swung into position beneath the die and the die brought down, by operation of the treadle, into contact with the heel-seat. While the die is in light contact with the heel-seat, the position of the shoe relatively to the die may be shifted, as determined by the judgment of 65 the operator, to bring the heel-seat and die into the proper operative relation, after which the pressure of the die is increased to prevent accidental displacement of the shoe, and the heel-seat forming pressure effected 70 by movement of the work support is then caused to take place. Conveniently and as illustrated, further movement of the treadle which lowers the die may be utilized to trip the clutch for applying the heavy molding 75 pressure to the heel-seat. To this end a yielding connection is provided between the treadle and the mechanism for moving the die, and a lost motion connection between the treadle and the tripping mechanism of the 80 clutch. Automatic means is provided for releasing the one-way clutch after the forming pressure is released. In the illustrated machine a cam acts on a lever which carries the clutch roll, the cam acting to depress the 85 roll and release the die during the second part of the cycle of the machine.

As usual in machines of this type, the forming pressure is applied by straightening a toggle one end of which is connected to the 90 shoe support and the other end of which is supported by a powerful spring. In order to vary the amount of pressure applied by the machine as required by different kinds of shoes, the illustrated machine is provided with means for imparting initial tension to 95 the spring and for varying the initial tension, such means being arranged for convenient adjustment by the operator and an indicator being provided, by observation of which the 100 amount of initial tension may be estimated.

105

In order to avoid as much movement of the die as would be necessary to take care of the various heights of lasts used in the various sizes of shoes, a height adjustment for the work support is provided which, as illustrated, is made by a plurality of distinct steps, the die member being employed to take up the distance between the steps. In this way excessive movement of the die, when operating upon small shoes, is avoided.

With these and other objects and features in view, the invention will now be described in connection with the accompanying drawings and pointed out in the claims.

15 In the drawings,

Fig. 1 is a side elevation of a machine embodying the present invention;

Fig. 2 is a detail in perspective of parts shown in Fig. 1;

20 Fig. 3 is a front elevation of one side of the machine, the other side, which is a substantial duplicate of the first side, being shown in outline; and

Fig. 4 is an elevation of a work support showing the shoe and die in section.

Referring to Fig. 1, the numeral 10 indicates the frame of the machine, secured to the upper part of which is a backwardly tilted framework comprising a head 11 rigidly supported by four heavy rods 12 and braced by diagonal members 13. Arranged for sliding movement in the head 11 is a die carrier 14. On the lower end of the die carrier is a die 15 having a stem 16 extending up into the die carrier and provided at one side with a slot and a recess (Fig. 4). Mounted in the die carrier is a spring pin 17 which enters the slot in the stem 16 to prevent turning of the die and also enters the recess to prevent the die from dropping out. By pulling outwardly on the pin 17, the die may be released, removed, and another die substituted for it. At its upper end the die carrier 14 has a pin-and-slot connection at 18 to a lever 20 pivoted at 22 to the head 11, and being connected between its ends at 24 to a treadle rod 26 which has a yielding connection to a treadle 28 pivoted to the frame at 30. The yielding connection comprises a yoke 32 pivoted to the lever 28, the rod 26 passing through the yoke and having thereon a spring 34 which is compressible by depression of the treadle between the yoke 32 and a nut on the end of the rod when movement of the rod is arrested. The treadle 28 is raised by a spring 36 which also acts through the yoke 32 and a collar 38 fixed on the rod 26 to move the die carrier 14 away from the shoe.

In treating the heel-seat of a shoe by the die 15, the last of the shoe is placed upon a last pin 40 (Fig. 4) which projects from a slide 42 having a dovetailed connection to a member 44. Movement of the slide 42 is in a direction transverse to the longitudinal medium plane of the shoe and is preferably

slightly curved about an axis extending longitudinally of the shoe and lying substantially in the plane of the heel-seat. The member 44 is pivoted at 46 to a head 50 of a shaft 52 which telescopes into a post 54. Between the head 50 and the member 44 is a screw 56 by adjustment of which the position of the member 44 about the pivot 46 may be varied. The screw 56 is maintained in adjusted position by a set screw 58. From Fig. 3 it will be seen that the screw 56 affords an adjustment by which the plane of the cone of the last resting on the slide 42 may be varied longitudinally of the shoe with respect to the plane of the face of the die 15 to ensure the proper distribution of pressure at the front and rear of the heel-seat. The shaft 52, which telescopes into the post 54, and the post itself are slotted at their lower parts to receive an adjusting member 60 which is pivoted at 62 to the shaft 52 and has a projecting finger piece 63. The lower edge of the member 60 is provided with a plurality of notches 64, 65, 66 which are at different distances from the pivot 62. A pin 68 is arranged transversely in the post 54 to be engaged by any one of the notches 64, 65, 66. Obviously, by moving the shaft 52 vertically and swinging the member 60 by its projecting finger piece 63, any one of the notches 64, 65, or 66 may be brought into engagement with the pin 68 and the height of the slide 42 varied by successive steps. The post 54 is secured by a pin 70 to the upper end of a shaft 72 which carries a set screw 74 for holding the pin 70 in place. The shaft 72 is arranged for longitudinal sliding movement with its axis in alinement with the longitudinal axis of the die carrier 14, these axes being tipped backwardly away from the operator at an angle of about ten degrees to the vertical so as to enable the operator more easily to inspect the shoe and die and determine their relative location. The lower end of the shaft 72 is connected at 78 to the upper link 80 of a toggle the lower link 82 of which is pivoted at 84 to a plunger 86 arranged for limited sliding movement in a cylindrical member 88. The plunger 86 is slotted at 90 to receive a pin 92 passing through the walls of the cylindrical member and through the slot in the plunger to limit movement of the plunger. Beneath the plunger 86 and within the member 88 is a very powerful spring 94 the upper end of which rests against the plunger 86 and the lower end of which rests upon a disk 96. A screw 98 is threaded through the lower end of the cylindrical member 88 to engage the disk 96 and carries a large gear 100 with which a pinion 102 meshes. The pinion 102 is fixed to the lower end of a shaft 104 arranged vertically and having a lower bearing 108 formed on the cylindrical member 88 and having at its upper end two bearings 110 and 112 (Fig. 3) formed on a bracket 114 secured at 116 to the ma- 125

chine frame. At its upper end the shaft 104 is provided with a hand-wheel 106 which may be turned to vary the initial tension of the spring 94. During application of this initial tension, movement of the plunger 86, against the lower end of which the spring bears, is prevented by the pin 92 which passes through the slot 90 of the plunger.

In practice it has been found satisfactory so to proportion the spring 94 and the screw 98 that the spring may be compressed one half inch by turning the hand-wheel, and that such compression will produce an initial tension of approximately 3000 pounds. The toggle 80, 82 is so constructed and arranged that straightening of the toggle, if upward movement of the shoe support is prevented, will depress the plunger 86 one half inch, so that a potential pressure of 3000 pounds may be obtained by straightening the toggle with no initial tension on the spring 94, and if the initial tension of the spring 94 is at the maximum a total pressure of 6000 pounds is obtainable by straightening of the toggle. Clearly, by adjustment of the hand-wheel the pressure obtainable may be varied from 3000 to 6000 pounds.

In order to indicate to the operator the amount of initial tension he has applied to the spring 94 by turning the hand-wheel 106, an indicating device, best shown in Fig. 3, is provided. On the shaft 104 between the bearings 110, 112, is a threaded sleeve 118 on which is a nut 120. Secured to the nut 120 is an indicating finger 122 which passes through a slot formed in a web 124 which connects the bearings, 110, 112. The finger 122 prevents the nut 120 from turning when the shaft is turned so that the nut will move vertically on the sleeve 118. A suitable scale 126 is provided adjacent to the finger 122 the vertical position of which on the scale indicates the amount of initial tension of the spring 94. Since the pinion 102 is small relatively to the gear 100, the movement of the nut 120 and finger 122 is greatly in excess of the actual movement of the disk 96 by the screw 98 by which the initial tension of the spring 94 is produced.

The toggle 80, 82 is straightened by power operated mechanism comprising an eccentric strap 130 connected at 132 to the middle joint of the toggle 80, 82 and embracing an eccentric 134 on a shaft 136. By means of a suitable one-half revolution clutch mechanism, the eccentric may be connected to a continuously rotated gear 138 with which a pinion 140 on a shaft 142 meshes. On the shaft 142 is a gear 144 which is in mesh with a pinion 146 of an electric motor 148. The clutch is tripped by outward movement of a clutch stop arm 150, which movement is effected by a downward movement of a rod 152 connected at 154 to the treadle 28. At its upper end the rod 152 has a lost-motion connection at 156 with the clutch stop arm. By reason of

the lost motion connection the treadle may be depressed a predetermined amount before the stop arm 150 is operated to trip the clutch.

Mechanism similar to that disclosed in my prior application above referred to is provided for preventing the eccentric from running ahead of its operating mechanism due to the action of the spring 94 while the pressure is being relieved.

For the purpose of locking the die carrier 14 against upward or regressive movement when the shoe support is raised, a roller clutch is provided. This clutch comprises a roll 160 which lies against an inclined, hardened face 162 on the frame and a face 164 formed by the hardened plate secured to the die carrier 14. Regression of the die carrier will, of course, be prevented by pinching the roll 160 between the upwardly converging surfaces 162, 164. In order that the roll may shift slightly to obtain a full bearing on the converging surfaces 162, 164, the roll is provided with trunnions at its ends which are journaled in blocks 166. The blocks are mounted in grooves 168 formed respectively in the inner faces of the two forward arms of levers 169, 170 which are fulcrumed on a pin 172 passing through the head 11, the grooves 168 extending lengthwise of the levers. This construction is best shown in Fig. 2. The rearwardly extending arms of the levers 169, 170 are connected at 174 to a yoke 176 on the upper end of a rod 177. The lower end of the rod is connected at 178 to an angle lever 180 pivoted to the frame 10 at 182. The angle lever carries a roll 184, which, at the proper time in the cycle of the machine, is engaged by a cam 186 which rotates with the eccentric 134. Movement of the lever by the cam 186 acts, through the rod 177, to push upwardly on the pivot 174 thus operating the levers 169, 170 to depress the roll 160 from engaging with the surfaces 162, 164 and allowing the die carrier 14 to be raised by the action of the spring 36 which acts to raise the treadle, the raising of the treadle by the spring 36 causing the yoke 32 to push upwardly on the collar 38 fixed on the rod 26 to raise the die carrier. The cam 186 is arranged to act on the angle lever 184 during the portion of the cycle in which the pressure is relieved and preferably after the shoe support has descended far enough so that there is no upward pressure upon the die carrier. Normally, that is, when the cam 186 is not acting, the roll 160 is maintained in position to prevent regression of the die carrier by a spring 192.

The operation of the machine is as follows: The operator places the last of a shoe, such as a turn shoe, the heel-seat of which has been fitted, upon the last pin 40, and swings the shoe and shoe support about the pivot 70 to locate the shoe longitudinally with respect to the die 15. If the space between the heel-seat 130

and the die is excessive so that too much movement of the treadle would be required to bring the die into contact with the heel-seat, the shoe and the telescoping shaft 52 are lifted 5 with respect to the rolls 54 and the adjusting member 60 swung so as to cause the notch 64 to engage the pin 68. If the work support is too high to permit the shoe to be swung under the die, the member would be adjusted to 10 cause the notch 66 to engage the pin 68; that is, the work support is so located by the step adjustment provided by the notches 64, 65, 66 and the plate 60, that the shoe will swing under the die without there being excessive 15 space between the die and the heel-seat. The treadle 28 is depressed and acts, through the rod 26 and the lever 20, to move the die carrier 14 downwardly to cause the die 15 to engage the heel-seat of the shoe. As the die approaches the shoe, the operator will make the necessary longitudinal and lateral adjustment 20 of the shoe with respect to the die so that the die will be properly located with respect to the heel-seat before the die is pressed too firmly against the heel-seat. The operator is greatly assisted in making these adjustments by the fact that the axes along which the movements of the die and shoe support are effected are inclined away from him at a sufficient 25 angle to give him readily a proper view of the die and heel-seat. When the proper relative positions of the die and heel-seat have been secured, the die is clamped firmly upon the heel-seat by further movement of 30 the treadle 28, this pressure being applied yieldingly by reason of the yielding connection between the treadle and the rod 26. When the lost-motion connection at 156 has been taken up by movement of the treadle, the 35 treadle acts to move the arm 150 and trip the clutch, whereupon the eccentric 134 acts to straighten the toggle 80, 82 and force the shoe support upwardly against the die which, of course, is prevented from regressive movement by the action of the roll 160. Since the 40 die is held from movement, the toggle compresses the spring 94 a predetermined amount, which pressure is applied to the shoe support. If the spring 94 is under initial 45 tension, the straightening of the toggle applies a predetermined additional tension to the spring. The machine stops with the shoe under pressure and remains in this condition while the operator places another shoe in the 50 opposite side of the machine. The treadle is then again depressed to trip the clutch, whereupon the parts are restored to normal position.

Having thus described my invention, what 60 I claim as new and desire to secure by Letters Patent of the United States is:

1. In a heel-seat forming machine, the combination of a heel-seat die arranged for vertical movement, a last support, means for moving the die toward the support to engage

the heel-seat of a shoe on the support so that the shoe and die may be properly located with respect to each other, means for holding the die against regression, means for raising the support to impress the die on the heel-seat of the shoe, and yielding means through which the support is operated for controlling the pressure of the shoe against the die. 70

2. In a heel-seat forming machine, the combination of a heel-seat die arranged for vertical movement, a last support, manual means for moving the die toward the support to engage the heel-seat of a shoe on the support so that the shoe and die may be properly located with respect to each other, means for holding the die against regression, power means for raising the support to impress the die on the heel-seat of the shoe, and a spring arranged to limit the pressure to which the heel-seat of the shoe is subjected between the support and the die. 80

3. In a heel-seat forming machine, the combination of a movable heel-seat die, a shoe support arranged for free positioning movement horizontally with respect to the die, a treadle for moving the die vertically to bring the shoe and die into contact and to apply sufficient pressure to hold the die and shoe in proper relative position, means for locking the die in position, and power means becoming operative upon further depression of the treadle for raising the support to force the die against the heel-seat material. 90

4. A machine for forming the heel-seats of shoes for the reception of wood heels having, in combination, a shoe support arranged to hold a shoe bottom up with the heel-seat of the shoe in full view of the operator, a die movable downwardly preliminarily against a shoe on the support with sufficient pressure to hold the shoe from accidental displacement after being positioned properly with respect to the die by the operator, means comprising a one-way clutch for preventing regression of the die, and power means for effecting upward movement of the shoe support toward the die to apply heel-seat forming pressure to the shoe. 100

5. A machine for forming the heel-seats of shoes for the reception of wood heels having, in combination, a shoe support for holding a shoe bottom up, a die movable downwardly manually toward the support, a clutch for preventing regressive movement of the die, power operated means for raising the shoe support to force the shoe against the die with heel-seat forming pressure and means for controlling said pressure. 110

6. A machine for forming the heel-seats of shoes for the reception of wood heels having, in combination, a shoe support for holding a shoe bottom up, a die carrier movable toward and from the shoe support, a one-way roller clutch acting directly on the die carrier to prevent movement of the carrier away 120

from the shoe, and power means for raising the shoe support to apply heel-seat forming pressure to the shoe.

7. A machine for forming the heel-seats of 5 shoes for the reception of wood heels having, in combination, a shoe support on which the shoe is presented bottom up with the heel-seat in view of the operator, a die movable manually downwardly against a shoe on the support with sufficient pressure to hold the shoe from accidental displacement after its heel-seat has been positioned properly with respect to the die, means comprising a one-way clutch for preventing regression of the die, power means for effecting upward movement of the shoe support to apply heel-seat forming pressure to the shoe, and means for releasing the one-way clutch after the heel-seat has been formed.

20 8. A machine for forming the heel-seats of shoes for the reception of wood heels having, in combination, a shoe support, a die movable manually against a shoe on the support with sufficient pressure to hold the shoe from accidental displacement after being positioned properly with respect to the die, means comprising a one-way clutch for preventing regression of the die, power means for effecting upward movement of the shoe support 25 to apply heel-seat forming pressure to the shoe, and means acting automatically to release the one-way clutch after the heel-seat has been formed.

9. A machine for forming the heel-seats of 35 shoes for the reception of wood heels having, in combination, a shoe support, a die carrier movable toward and from the shoe support, a roller clutch acting directly on the die carrier to prevent movement of the carrier away 40 from the shoe, power means for raising the shoe support to apply heel-seat forming pressure to the shoe, and power means operating during that portion of the cycle while the pressure on the shoe is being released for 45 releasing the roller clutch.

10. A machine for forming the heel-seats of shoes for the reception of wood heels having, in combination, a shoe support, eccentric and toggle mechanism for operating the 50 shoe support, a die and die carrier movable toward the shoe support, a roll adapted to engage surfaces on the frame and the die carrier for preventing movement of the die carrier away from the shoe support, a lever 55 by which the roll is moved out of engagement with the frame and carrier, and cam means for operating the lever to move the roll.

11. A machine for forming the heel-seats of shoes for the reception of wood heels having, in combination, a shoe support, eccentric and toggle mechanism for operating the shoe support, a die and die carrier movable toward the shoe support, a roll adapted to engage the surfaces on the frame and the 60 die carrier for preventing movement of the

die carrier away from the shoe support, a pair of levers between the ends of which the roll is mounted so that by movement of the levers the roll will be withdrawn from engagement with the frame and carrier, and 70 cam means for operating the levers to move the roll.

12. A machine for forming the heel-seats of shoes for the reception of wood heels having, in combination, a shoe support, eccentric and toggle mechanism for operating the shoe support, a die and die carrier movable toward the shoe support, a roll arranged to engage upwardly converging surfaces on the frame and die carrier to lock the die carrier 80 against upward movement, a pair of levers between which the roll is mounted so as to permit lateral movement of the roll and to require movement of the roll vertically with the levers, and cam operated mechanism connected to the opposite ends of the levers to move the roll downwardly away from the converging surfaces.

13. A machine for forming the heel-seats of shoes for the reception of wood heels having, in combination, a shoe support, a die carrier movable toward and from the shoe support, means for preventing regressive movement of the carrier, a treadle, mechanism including a yielding connection between the treadle and the carrier for moving the carrier toward the shoe, power means for moving the shoe support toward the die to apply heel-seat forming pressure to the shoe, a clutch for operating the power means, and a lost motion 90 connection between the treadle and the clutch whereby the power means is set in operation by movement of the treadle after the die has been brought into contact with the shoe, such movement being permitted by the yielding connection between the treadle and the die carrier.

14. A machine for forming the heel-seats of shoes for the reception of wood heels having, in combination, a shoe support, a die carrier movable toward and from the shoe support, a heel-seat die on the carrier, a treadle mechanism including a yielding connection between the treadle and the carrier for moving the carrier toward the shoe, means for preventing reverse movement of the carrier, power means for moving the shoe support toward the die to apply heel-seat forming pressure to the shoe, a clutch for operating the power means, a lost-motion connection between the treadle and the clutch whereby the power means is set in operation by movement of the treadle after the die has been brought into contact with the shoe, such movement being permitted by the yielding connection between the treadle and the carrier, and 100 a cam operating after the power pressure is relieved to release the die carrier and permit it to be moved away from the shoe.

15. A machine for forming the heel-seats 110 of shoes for the reception of wood heels having, in combination, a shoe support, a die carrier movable toward and from the shoe support, a heel-seat die on the carrier, a treadle mechanism including a yielding connection between the treadle and the carrier for moving the carrier toward the shoe, means for preventing reverse movement of the carrier, power means for moving the shoe support toward the die to apply heel-seat forming pressure to the shoe, a clutch for operating the power means, a lost-motion connection between the treadle and the clutch whereby the power means is set in operation by movement of the treadle after the die has been brought into contact with the shoe, such movement being permitted by the yielding connection between the treadle and the carrier, and a cam operating after the power pressure is relieved to release the die carrier and permit it to be moved away from the shoe.

16. A machine for forming the heel-seats 120

of shoes for the reception of wood heels having, in combination, a shoe support constructed and arranged to hold a shoe and last bottom up with the heel-seat in view of the operator, a heel-seat forming die, power operated means for relatively moving the shoe support and the die to apply heel-seat forming pressure to the heel-seat of the shoe, a heavy spring by which such pressure is applied, and means for varying the initial tension of the spring to control the pressure to which the heel-seat is subjected.

16. In a machine for forming the heel-seats of shoes for the reception of wood heels, the combination of a heel-seat die and a shoe support relatively movable for applying pressure to the work, a toggle for moving one of said parts, a heavy spring forming an abutment for one end of the toggle, means for varying the initial tension of the spring, and means for indicating to the operator the amount of initial tension under which the spring is placed.

17. In a heel-seat forming machine, the

combination of relatively movable members including a heel-seat die and a shoe support for applying pressure to the shoe, a toggle for moving one of said members, a heavy spring forming an abutment for one end of the toggle, and a screw and gearing arranged to be readily accessible to the operator for adjusting the initial tension of the spring to vary the pressure between said members.

18. In a heel-seat forming machine, the combination of relatively movable members including a heel-seat die and a shoe support for applying pressure to the shoe, a toggle for moving one of said members, a heavy spring forming an abutment for one end of the toggle, means constructed and arranged for convenient operation by the operator to vary the initial tension of the spring, and an indicator operated by the adjusting means by observation of which the amount of initial tension may be estimated.

In testimony whereof I have signed my name to this specification:

RENÉ E. DUPLESSIS.
